UNITED STATES PATENT OFFICE.

CLIFFORD TRAUT, OF NEWPORT, KENTUCKY, ASSIGNOR TO THE HIGGIN MANUFACTURING COMPANY, OF NEWPORT, KENTUCKY, A CORPORATION OF WEST VIRGINIA.

ACCESS-PANEL STRUCTURE.

Application filed June 15, 1927. Serial No. 198,920.

My invention relates to access panels, and particularly to improvements in the means provided for articulating such panels in a frame in a wall structure.

5 It is the object of my invention to provide a double leafed hinged structure in which guiding means is so associated with the hinges, that the hinges will be controlled in a definite sequence of movements.

10 The above and other advantages to which reference will be made during the ensuing disclosure I accomplish by that certain arrangement and combination of parts of which I have illustrated a preferred embodiment.

In the drawings:—

Figure 1 is a side elevation taken from the side of the panel which faces the wall within which it is to be secured.

20 Figure 2 is a section taken along the lines 2—2 in Figure 1.

I have shown the access panel structure having a frame composed of walls 1 forming a rectangular enclosure. The walls 25 are reinforced with the angular strips 2 on the inside of the walls, and the angular strips 3 on the outside of the walls. The strips 2 have flat front surface portions against which the articulated panel 30 4 abuts when in closed position. The angle strips 3 have flanged portions which seat within the wall structure thereby holding the frame within the wall. The hinges for the panel are supported on angular brackets 5 which are shown as welded to the angle strips 2. Other means of mounting the 35 hinge supports, however, may be used. The hinges are double leafed, having the inner leaves 6 and the outer leaves 7 articulated together as indicated at 8 with a pintle.

40 The object of the double hinge leaf is to permit a full opening of the panel, and a closing thereof, so as to lie flush with the wall, without exposing any part of the hinge when closed. An ordinary hinge would have to be exposed at the knuckle, and this would result in a failure to have all of the parts of the panel and its mounting flush with the wall.

45 50 This type of access panel and frame is usually employed in building walls in order to form a convenient means of permitting plumbers and repair men to get at the plumbing, electric wiring or other fixtures.

55 When the panel is closed, it can be ren-

dered inconspicuous from the exterior, and if a lock is used such as indicated at 9, which may be unlocked by the insertion of a screw driver, the hole may be concealed with the rest of the panel. It is usually 60 the practice to conceal the panel from the exterior of the wall by means of wall paper, or to paint the panel like the walls, with the cracks puttied, if desired. It may also be left exposed, and being only a small unob- 65 structive object, it is scarcely visible.

The particular feature of my invention which, as far as I am aware, is broadly new, is the provision of guides which will enforce the proper movement of the panel 70 during its use. I have shown the angle guide members 10 formed with reinforcing corrugations 11 welded to the supporting plates for the outer of the hinge leaves. In the dotted lines in Figure 2 the posi- 75 tion of the guide members 9 almost at the closed position of the panel is shown. If, without pulling outwardly on the panel in the direction of its width, a mechanic attempts to swing the panel in an arc, the 80 surface of the guide bears against the surface of the outer of the hinge leaves, thereby preventing such movement. It is only when the panel has been pulled outwardly in the direction of its width that the guide 85 is moved out from a position in which it frictionally engages the outer of the hinge leaves. In this position the panel may then be swung out and its outer surface swung around until it lies in alignment with the 90 wall. By ensuring that the mechanic moves the panel through these two cycles of movement, first the outward pull, and then the swinging movement, the panel may 95 lie flush with the wall surface and yet will swing wide open against the surface of the wall.

It should also be noted that without guides for the hinge leaves, one pair of hinges might articulate in one direction 100 and the other in another, so that it would be very difficult to make the panel seat properly in the frame when it had once been swung open.

Having thus described my invention what 105 I claim as new and desire to secure by Letters Patent is:—

1. In an access panel structure, in combination with a frame, and a panel adapted to fit within the frame, a double leafed hinge 110

for mounting the panel on the frame, and guiding means for the leaves of said hinge for preventing an arcuate movement thereof prior to the extension of the leaves into substantial alignment, said guiding means extending from said panel.

2. In an access panel structure, in combination with a frame, and a panel adapted to fit within the frame, a double leafed hinge for mounting the panel on the frame, and guiding means for the leaves of said hinge for preventing an arcuate movement thereof prior to the extension of the leaves into substantial alignment, said guiding means comprising a plate mounted at such an angle as to lie in parallel alignment with the outer of the leaves of the hinge during completely closed position.

3. A hinge for an access panel and frame comprising articulated leaves, means for mounting an outer leaf on the panel, and means for mounting an inner leaf on the frame, and means for guiding the leaves into an extended position prior to the arcuate articulation thereof, said means comprising

ing a plate mounted at such an angle as to lie in parallel alignment with the outer leaf prior to the extension of said leaves.

4. A hinge for an access panel and frame comprising articulated leaves, means for mounting an outer leaf on the panel, and means for mounting an inner leaf on the frame, and means for guiding the leaves into an extended position prior to the arcuate articulation thereof, said means comprising a plate disposed so as to frictionally bear against the outer hinge leaf during completely closed position.

5. In an access panel structure, a frame adapted to be mounted in a recess in a wall, a panel extendible from the frame mounted therein, means for articulating the panel in the frame, comprising a double leafed hinge extendible to a position in which the panel will not bear against the frame during the articulated movement of said panel, and means extending from said panel for assuring the extension of said panel prior to the articulated movement thereof.

CLIFFORD TRAUT.
